GAME APPARATUS

Charles B. Gamble, Minneapolis, Minn.

Application March 17, 1931. Serial No. 523,212

8 Claims. (Cl. 265—20)

My invention relates to an indoor game device and the object of the invention is to provide an apparatus by means of which a game, such as golf, can be played indoors using the same variety 5 of clubs that would be used in an out-of-door game, as required by the yardage of the different holes on any existing course that might be selected for use in playing the game or one laid out on paper with the holes varied in length according to the fancy of the user of the device.

A further and particular object of my invention is to provide an apparatus having incorporated therein a registering mechanism whereby the player of the game in using different clubs 15 can determine with a reasonable degree of accuracy the distance obtained with each club and the number of strokes necessary to reach a green in a hole of a certain length, the distance to be obtained being the deciding factor in the player's 20 selection of his club for each stroke.

A further object is to provide a game apparatus of comparatively simple, inexpensive construction which can be easily and quickly set up and has no delicate parts to be easily broken or 25 arranged.

A further object is to provide a game apparatus which, while primarily designed for use in playing a game of indoor golf, may be employed with suitable modifications, in other games where a 30 ball is discharged or driven against a yielding surface.

Other objects will appear from the following description. In the accompanying drawings forming part of this specification,

Figure 1 is a front elevation of the apparatus embodying my invention;

Figure 2 is a side elevation of the same, the dotted lines indicating the position assumed by the flexible sheet and the levers connected therewith when the sheet is struck by a ball or other object;

Figure 3 is a rear view of the apparatus; and, Figure 4 is a sectional view on the line 4—4 of Figure 2.

In the drawings, 2 represents a suitable base and 3 an upright standard mounted thereon. The base has sufficient weight to hold the frame of the apparatus in a suitable upright position while permitting it to be moved from place to place 50 for the purpose of adjusting the frame in the desired location for playing the game. A spider 4 is secured to the upper portion of the standard 3 and has a series of arms 5 radiating therefrom. These arms are preferably inclined forwardly as indicated in Figure 2 and I prefer to provide four

of them, though a greater or lesser number may be employed if preferred. As shown, the arms extend radially a suitable distance from the spider depending upon the desired diameter of the frame, the inner ends of the arms being rigidly secured to the spider by any suitable means. The outer ends of the arms preferably have flat surfaces 6 and levers 7 are seated on these surfaces and are connected to side faces of the arms by hinges 8. The levers are mounted at any suitable point intermediate to their ends on the radial arms so that each lever will have a portion projecting in front and in the rear of the arm, the flat end surface of each arm forming a stop to limit the inwardly swinging movement of the rear end of each lever.

The forward ends of the levers have suitable flexible tabs 9 secured at one end thereto, the free ends of the tabs being stitched or otherwise secured to a flexible sheet 10 of canvas or any other suitable material. The canvas is thus supported or suspended at four points, one point of attachment to each lever to which the force or impact of the blow upon the sheet will be instantly transmitted. This sheet may be of any suitable size according to the desired distance between the supporting levers.

Normally the sheet will hang loosely in the position indicated by full lines in Figure 2. When, however, it is struck by a driven ball or other object it will assume the dotted line position, or substantially so, and thereupon the force of the impact will be transmitted to the levers to tilt them on their supporting pivots, swing the forward ends inwardly and the rear ends outwardly as indicated by dotted lines in Figure 2.

The sheet preferably has an extension 11 which depends below the lower supporting levers in front of the base and standard for the purpose of deflecting a ball that may have been topped or driven at such an angle that it does not strike the sheet between its points of suspension, and a suitable back stop may be provided in the rear of the frame to catch the balls that miss entirely the lever supported sheet. It is evident that in driving a golf ball against this sheet the force of the impact will determine the degree of travel of the supporting levers. A hard driven ball will, of course, strike the sheet with greater force and this force transmitted to the levers will exert a greater pull upon them and tilt these levers to a greater degree than when the sheet is struck by a ball driven with less force. A player, therefore, knowing approximately the distance he can obtain with the different clubs used by him can,

through the movement of the levers when the sheet is struck by a ball, indicate quite accurately the flight of a ball in yards by a suitable mechanism connected with and actuated by the 5 tilting levers. The sum of the movements of these levers is commensurate with the force of the blow on the sheet supported by them and when this movement is transmitted to a suitable registering device the distance indicated thereby 10 will be approximately the distance the player would obtain in playing the out-of-door game.

Various devices may be utilized for registering the degree of movement of the levers and the impact of the ball on the sheet supported by 15 these levers but I have devised a simple, inexpensive mechanism for this purpose that will be operated with a minimum of friction and lost motion and which is comparatively simple in construction and not easily broken or disarranged. 20 This preferred registering device I will now proceed to describe in detail.

The spider 4 has a hub portion 12 provided with horizontal radiating arms 13 and 14 and a similar upright arm 15. On these arms sheaves 25 16, 17 and 18 are mounted, the sheaves 16 and 17 being upon substantially the same level upon opposite sides of the hub member 12 and the sheave 18 above and intermediate the other sheaves, as shown plainly in Figure 3. A stud 19 is tapped into the hub member 12 and projects horizontally therefrom toward the rear of the game apparatus. A drum 20 is loosely mounted on this stud and a hub 21 is also loosely mounted on the stud and held in frictional engagement 30 with a disc 22 secured on the stud by means of a compression spring 23. An indicator 24 is mounted in the hub 21 and projects horizontally therefrom in its normal position, as shown in Figure 1, this indicator being adapted to move over the graduations on a scale that is provided in the rear of the game apparatus, the figures of the scale representing yards of distance and are placed upon a suitable sheet or other means 35 supported in the rear of the apparatus. The 40 position of these graduations, as usual in devices of this kind, will be determined by experimentation. If the player stands in front of the flexible sheet and selects a certain club with which he has found in cut-of-door use he can obtain a 45 certain distance in yards, then, if the apparatus is working properly, and, he connects fairly with the ball and believes from its impact with the sheet that the ball would have been driven, say 150 yards on the fairway, he can note the 50 position assumed by the indicator of the apparatus and mark that spot with the graduations corresponding to the distance he believes he has obtained and by experimenting with the different 55 wood and iron clubs he can determine with reasonable accuracy the proper position of the graduations on the scale of yards.

A threaded rod 26 is provided in the hub 21 on the other side of its axis and a weight 27 is adjustably mounted on this rod by means of which 60 the weight of the indicator 24 may be counterbalanced so that it will not be necessary to overcome the force of gravity of the indicator before its movement over the graduations of the scale begins.

70 A pin 28 is mounted in the drum 20 and projects rearwardly under the indicator 24, as shown plainly in Figure 4, so that movement of the drum produces a corresponding movement of the indicator 24 and the hub 21. The frictional engagement of the hub 21 with the disc 22 will

retain the indicator 24 at the maximum point to which the drum has moved it.

It is necessary to provide suitable means for transmitting or transferring the travel or stroke of the pivoted levers to the indicating arm or rod and this I prefer to accomplish by mounting sheaves A, B, C, and D in the rear end portions of the lever 7 so that there will be a sheave and its supporting lever in the rear of each corner of the sheet with which the ball or other object impacts. A suitable flexible cable 29 is provided for running engagement with the sheaves, as above described, and preferably this cable is stretched between the sheaves in the following manner:

Take for instance, the sheave A at the upper left hand corner of Figure 3. The cable is passed around this sheave until a point about the middle of the cable is in engagement with the sheave. One end of the cable is then stretched around the sheave 17 near the center of the apparatus, thence to the sheave C at the lower left hand corner of Figure 3, then back to the drum 20. The other end of the cable is passed under the sheave 18, thence to sheave B, back to the sheave 16, 130 from thence outwardly to the sheave D and then to the drum 20, where the two ends of the cable are joined and passed around the drum a suitable number of times and then connected to the weights 30, made up as shown in Figure 3, of a number of sections, and adapted to be increased or decreased in number as desired.

These weights will hold the cable under tension and draw inwardly on the levers so that normally each lever will be seated against the flat end 135 surface of the arm 5 on which it is pivoted, and this will prevent any tension being applied to the sheet connecting the forward ends of the levers allowing the sheet to hang loosely between these levers and avoiding the danger of rebound of a 140 ball resulting from striking a surface that is drawn taut or under tension. On the contrary, when the ball strikes this suspended sheet there will be a sufficient yielding action of the sheet to eliminate rebound and at the same time the force 145 of the impact will be transmitted through the sheet to the levers without any appreciable loss in the force of the impact. The convolutions of the cable on the drum will prevent slippage thereon and the pull of the levers on the cable 150 will be instantly transmitted to the drum to cause its rotation against the pull of the weight and move the indicator over the graduations in the rear of the apparatus. The distance traveled by the indicator on the graduations will, of course, depend upon the force of the impact of the ball with the flexible sheet. If the ball is struck with a force which would drive it, for instance 200 yards down the fairway, then if the 155 calibration is substantially correct and the mechanism in proper working order, the indicator should stop approximately over or opposite the 200 mark on the dial, thus indicating to the player that the ball has been driven approximately 200 yards. If the particular hole that is being 160 played is 400 yards in length then the player will understand that he has another shot requiring, usually, a brassie shot to reach the green and, if upon playing the second shot with the brassie or any other club that may be selected for the 165 purpose, the mechanism indicates for a second time a distance of 200 yards, the player will assume that his ball has reached the green. Previously, however, to this second shot it will be necessary for him to return the indicator hand to 170

its normal or zero position and this is accomplished by means of a cord 31 that is connected to the hub 21 and passes over suitable pulleys 32 to a point within the reach of the player and is provided with a ring 33 or other suitable hand grip by means of which the player standing on the tee or other playing position can pull the cord 31, reverse the movement of the hub 21 and return the indicator hand and drum 31 to normal position, as illustrated in Figure 3.

If for any reason, when the player fails to reach the green with the second shot, as above described, and instead of making 200 yards drives the ball only 150, he will then have a 50 yard shot to reach the green and, having previously returned the indicator to its normal position, he will select a suitable club according to the distance usually obtained by him with that club in playing the game out-of-doors and will then make his shot and if the distance to go is 50 yards and the indicator stops opposite this mark on the dial, then the player will assume that his ball is dead to the hole. If the distance to go is 50 yards and the indicator moves to 75 or 80, then the player will understand that he has over-shot the green as many yards as the register indicates in excess of 50 and it will then be necessary for him to play back to the green. If instead of over-playing the green the scale indicates that the ball has been driven 40 yards instead of 50, the required distance, then the player may assume that his ball is within ten yards of the cup or on the edge of the green and within putting distance of the cup. He will then place the ball on a putting surface that is provided in connection with the game apparatus and putt in the usual way to a cup that is located approximately the distance from where the ball is dropped that the cup of the green is assumed to be from the point at the edge of the green where the ball has come to rest.

In this way a player or group of players can play an indoor game of golf using holes of any desired length and playing the game with any club that the player may have in his bag, and, while there may be some difference in the distance of flight indicated on the dial from that which the player would actually obtain in an out-of-door game, nevertheless the mechanism may be so adjusted that the distances indicated will be approximately correct and, of course, will be just as fair for one player as for another and at any time the distances obtained, as indicated on the scale, may be increased or decreased by varying the weight attached to the cable.

If the weight is increased then there will be greater resistance to the movement of the levers supporting the flexible sheet with which the ball impacts. The travel of the drum will be less and there will be a corresponding decrease in the movement of the indicator. If, on the other hand, the weight is reduced there will be correspondingly less resistance to the movement of the levers under the impact of a ball on the sheet and the indicator will register a correspondingly higher graduation on the scale. Thus the user of the apparatus can with little difficulty determine the proper weight to be applied to the cable to yieldingly resist movement of the levers, under the estimated force of impact of a ball, to register on the dial approximately the distance of flight of the ball out-of-doors if struck with the same force.

From the foregoing description, it will be noted that the rotary movement of the drum caused by the oscillation of the levers 7 will be propor-

tional to the sum of the individual lever movement. For instance, if the point of impact of the ball is in the exact center of the sheet, each lever will move approximately the same distance. On the other hand, if the point of impact of the ball should be to one side of the center or close to one of the levers, the effect will be greater on this particular lever and less on the others. The sum, however, of the lever movement in both cases will be approximately equal and will therefore cause an approximately equal rotation of the drum. This feature of the device is quite important as the accuracy of the indicating mechanism is not affected even though the ball does not strike the sheet in the center. The result is practically the same when the sheet is struck at any point on its surface. The player, therefore, has a surface of considerable area against which to drive the ball and the accuracy of the indicating device will not be impaired materially even though the ball may strike the canvas above or below or on either side of the middle portion. The arrangement is such that when the canvas is struck at any point by an object traveling at a given speed a correspondingly equal movement of the indicating mechanism will be produced.

In various ways the details of construction herein shown and described may be modified and still be within the scope of my invention.

I claim as my invention:

1. The combination with a plurality of radial arms, of levers pivoted intermediate to their ends on the outer portions of said arms, a flexible sheet loosely supported by said levers on one side of their pivots, the impact of an object striking said sheet causing said levers to be tilted on their pivots, and a mechanism connected with said levers on the opposite side of their pivots from said sheet for indicating a distance in yards commensurate with the aggregate tilting movement of said levers. 105

2. The combination with a frame having a plurality of radial arms, of levers hinged to the outer portions of said arms and normally seated upon the outer ends of said arms transversely with respect thereto, a flexible sheet loosely supported by said levers on one side of their pivots whereby the impact of a ball striking said sheet will tilt said levers on their pivots, the ends of said arms forming stops for said levers and preventing said sheet from being drawn taut, and an indicating mechanism connected with said levers on the other side of their pivots. 120

3. The combination of a suitable support, of a plurality of levers pivoted thereon, a flexible sheet connected to said levers on one side of their pivots, sheaves mounted in said levers on the other side of their pivots, a plurality of sheaves mounted in said support, a rotating drum, a cable having a running connection with said sheaves and being wrapped around said drum, a weight suspended by said cable from said drum for yieldingly resisting the tilting of said levers on their pivots, and a registering device having means operated by the movement of said drum when said levers are tilted upon the impact of a ball with said flexible sheet. 130

4. The combination with an upright standard, of a plurality of arms radiating therefrom, levers pivoted intermediate to their ends on the outer portions of said arms, a flexible sheet having flexible connections to the forward ends of said levers and adapted to transmit the impact of a golf ball on said sheet to said levers, a revolving drum on said standard, a plurality of sheaves 145

- on said standard, a cable having running connections with said levers in the rear of said arms and with said sheaves and wrapped around said drum, a weight suspended by said cable below said drum whereby a tension will be applied to said cable to yieldingly resist the impact of a ball striking said sheet, and a registering device having means operated by the movement of said drum when said levers are actuated through the impact of a ball on said sheet. 80
5. The combination with a support and a plurality of opposed oscillatable members thereon, of a flexible sheet connected to said members and adapted when struck by a flying object to transmit a pull to said members and cause tilting movement thereof, means connected to said members to yieldingly resist pull of said sheet thereon, means whereby tensioning of said sheet by the pull of said yielding means on said members is prevented, and a registering mechanism connected with said yielding means. 85
10. The combination with a supporting means, of lever members pivotally mounted at spaced points thereupon, a flexible sheet connected at diametrically opposite points to said lever members, the arrangement being such that when said sheet is struck by a flying object, a pull will be imparted to said members and tilt them on their pivots proportionally to their proximity to the 90
15. The combination with a supporting means, of lever members pivotally mounted at spaced points thereupon, a flexible sheet connected at diametrically opposite points to said lever members, the arrangement being such that when said sheet is struck by a flying object, a pull will be imparted to said members and tilt them on their pivots proportionally to their proximity to the 95
20. The combination with a supporting means, of lever members pivotally mounted at spaced points thereupon, a flexible sheet connected at diametrically opposite points to said lever members, the arrangement being such that when said sheet is struck by a flying object, a pull will be imparted to said members and tilt them on their pivots proportionally to their proximity to the 100
25. The combination with a supporting means, of lever members pivotally mounted at spaced points thereupon, a flexible sheet connected at diametrically opposite points to said lever members, the arrangement being such that when said sheet is struck by a flying object, a pull will be imparted to said members and tilt them on their pivots proportionally to their proximity to the 105
30. The combination with a supporting means, of lever members pivotally mounted at spaced points thereupon, a flexible sheet connected at diametrically opposite points to said lever members, the arrangement being such that when said sheet is struck by a flying object, a pull will be imparted to said members and tilt them on their pivots proportionally to their proximity to the 110
35. The combination with a supporting means, of lever members pivotally mounted at spaced points thereupon, a flexible sheet connected at diametrically opposite points to said lever members, the arrangement being such that when said sheet is struck by a flying object, a pull will be imparted to said members and tilt them on their pivots proportionally to their proximity to the 115
40. The combination with a supporting means, of lever members pivotally mounted at spaced points thereupon, a flexible sheet connected at diametrically opposite points to said lever members, the arrangement being such that when said sheet is struck by a flying object, a pull will be imparted to said members and tilt them on their pivots proportionally to their proximity to the 120
45. The combination with a supporting means, of lever members pivotally mounted at spaced points thereupon, a flexible sheet connected at diametrically opposite points to said lever members, the arrangement being such that when said sheet is struck by a flying object, a pull will be imparted to said members and tilt them on their pivots proportionally to their proximity to the 125
50. The combination with a supporting means, of lever members pivotally mounted at spaced points thereupon, a flexible sheet connected at diametrically opposite points to said lever members, the arrangement being such that when said sheet is struck by a flying object, a pull will be imparted to said members and tilt them on their pivots proportionally to their proximity to the 130
55. The combination with a supporting means, of lever members pivotally mounted at spaced points thereupon, a flexible sheet connected at diametrically opposite points to said lever members, the arrangement being such that when said sheet is struck by a flying object, a pull will be imparted to said members and tilt them on their pivots proportionally to their proximity to the 135
60. The combination with a supporting means, of lever members pivotally mounted at spaced points thereupon, a flexible sheet connected at diametrically opposite points to said lever members, the arrangement being such that when said sheet is struck by a flying object, a pull will be imparted to said members and tilt them on their pivots proportionally to their proximity to the 140
65. The combination with a supporting means, of lever members pivotally mounted at spaced points thereupon, a flexible sheet connected at diametrically opposite points to said lever members, the arrangement being such that when said sheet is struck by a flying object, a pull will be imparted to said members and tilt them on their pivots proportionally to their proximity to the 145
70. The combination with a supporting means, of lever members pivotally mounted at spaced points thereupon, a flexible sheet connected at diametrically opposite points to said lever members, the arrangement being such that when said sheet is struck by a flying object, a pull will be imparted to said members and tilt them on their pivots proportionally to their proximity to the 150

CHARLES B. GAMBLE.
